UNITED STATES PATENT OFFICE.

JOSEPH F. HEWITT, OF ALLEGHENY, PENNSYLVANIA.

DESIGN FOR A GAS-BURNER.

SPECIFICATION forming part of Design No. 24,241, dated April 23, 1895.

Application filed February 20, 1895. Serial No. 539,144. Term of patent 7 years.

To all whom it may concern:

Be it known that I, JOSEPH F. HEWITT, a citizen of the United States, residing at Allegheny, in the county of Allegheny and State 5 of Pennsylvania, have invented and produced a new and original Design for Gas-Burners; and I do hereby declare the following to be a full, clear, and exact description of the same, reference being had to the accompanying 10 drawings, forming a part thereof.

The leading feature of the design for a burner consists in its general contour comprising a curved front and the approximately 15 flat back having as a whole a general resemblance to a chip cut from a tree.

Numerals 1 denotes a slightly convex front of the burner having a square or approximately 20 square plan. Said front is provided with small openings 2 and has fanciful imitations of small knots in or near the corrugated surface, and 3 indicates a cylindrical opening.

5 denotes a straight transverse portion at the rear of the burner. 25

The appearance of the front of the burner resembles in a general way the surface of a chip or section from a large log placed on end and is of a character adapted by association and otherwise to produce a pleasing effect. 30 Further as shown the burner has a curved contour extending toward its front throughout practically its entire extent, which conformation considered in itself imparts a pleasing and useful effect. 35

What I claim is—

The design for a gas burner as herein shown and described.

In testimony whereof I have affixed my signature in presence of two witnesses.

JOSEPH F. HEWITT.
